HINGE

Robert B. Battersby, Darien, Conn., assignor to
Plastic Manufacturers, Incorporated, Stamford, Conn., a corporation of Connecticut

Application November 1, 1946, Serial No. 707,075

8 Claims. (Cl. 220—31)

1

The present invention relates in general to hinges and more especially to an improved articulated joint for molded plastic articles.

An object of the invention is to provide a receptacle comprising a base and cover wherein the cover is secured to the base by improved articulated means which is of simple construction and provides a smooth-acting, snugly-fitted hinged joint.

A further object of the invention is to provide an improved hinge for plastic receptacles.

A still further object of the invention is to provide an improved all-plastic hinge for a molded display case wherein the separable elements of the hinge are molded integrally with corresponding parts of the display case and are joined in operative relationship by a plastic pin.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a side elevation of a molded plastic receptacle embodying the improved plastic hinge of this invention;

Fig. 2 is a bottom plan view of the receptacle shown in Fig. 1;

Fig. 3 is an enlarged sectional end elevation of the receptacle on line 3—3 of Fig. 1;

Fig. 4 is an enlarged fragmentary sectional view of the improved plastic hinge of this invention on line 4—4 of Fig. 2;

Fig. 5 is a fragmentary perspective view of the underside of the base of the receptacle showing the guide-ribs of the hinged joint;

Fig. 6 is an enlarged perspective view of the rear edge of the cover showing the integral hinge-tongue thereof;

Fig. 7 is an enlarged fragmentary view of a modification of the plastic hinge wherein the lower end of the tongues of the cover are bifurcated, so as to engage on opposite sides respectively of a single guide-rib molded on the underside of the base;

Fig. 8 is a fragmentary sectional elevation of the hinge on line 8—8 of Fig. 7;

Fig. 9 is an enlarged fragmentary sectional elevation of the plastic hinge embodying modifications in the shape of the guide-ribs, due to the thickness of the tongue of the plastic cover; and

Fig. 10 is a fragmentary perspective view of

one corner of the base showing one of the hinge slots therein.

Referring to the drawings, the latter show an exemplary embodiment of the invention as used on a box-like receptacle or display case such as illustrated in Figs. 1 and 2. The receptacle may be formed of any suitable material such, for example, as wood, glass, porcelain, rubber, metal and the like, but for the purposes of illustration is fashioned of a moldable plastic material having the physical characteristics of polystyrene and related plastics, and comprises a one-piece molded base 11 consisting preferably of an opaque plastic material and comprising a substantially-rectangular platform 12 circumscribed about its perimeter by a skirt 13. The skirt 13 is joined to the platform by a substantially-vertical wall 14, the latter being formed integrally with the platform and depending therefrom at substantially right angles to the horizontal plane thereof. The platform 11 and vertical wall 14 are substantially planar surfaces of uniform cross section, whereas the skirt 13 is substantially quadrant-shaped in cross section, as shown clearly in Fig. 4.

Formed at one end of the base 11 and more particularly in the top of the skirt 13 immediately adjacent the outer face of the wall 14 of the base, are a pair of rectangular slots 15 (see Fig. 3) which are substantially equally spaced laterally on opposite sides of the longitudinal axis of the base 11. As shown in Fig. 10, each slot 15 pierces vertically through the skirt 13 and extends horizontally through the adjacent outer face of the wall 14, the width and height of the vertical and horizontal reaches respectively of the slot 15 being substantially equal and slightly greater than the thickness of the receptacle-cover, for the purpose hereinafter described. Although the use of two laterally-spaced slots is preferred, it will be understood that it is within the purview of the invention to employ more or less than two slots.

The improved articulated joint of this invention is shown generally at 16, one element of which comprises a projection or rib 17 of fin-like proportions molded integrally or otherwise formed on the underside of the base 11, one rib 17 being provided at each edge of each slot 15, as shown clearly in Figs. 3 and 5. Each projection constitutes an arcuate substantially-quadrant-shaped cam-surface 18 subtending an angle of substantially 90°, the horizontal reach of each cam-surface being extended to intersect the underside of the skirt 13, while the vertical reach

of the cam-surface is adapted to intersect the underside of the platform 11. As thus formed, each pair of guide-ribs 17 projects inwardly in spaced parallel relationship and at opposite edges of each slot 15, the cam-surfaces 18 of the ribs being adapted to guide or control the rotational movement of the cover of a receptacle as the former is swung to and from its closed and open positions respectively relative thereto. The length of the radius r of each quadrant-shaped cam-surface is predetermined, depending upon such factors as the depth of the base 11, the preferred length of the hinge elements 23 of the cover (hereinafter described) and the thickness thereof. Where the thickness of the hinge elements of the cover is of the order of $\frac{1}{16}$ or less, the cam-surface 18 of each rib 17 may be the true arc of a circle struck on a center corresponding substantially to the point of intersection of the axes of the horizontal and vertical reaches of the slots 15, as indicated by the broken lines in Fig. 4.

The cover 19 of the receptacle is a one-piece substantially-rectangular molded member consisting preferably of a transparent plastic material and comprising two substantially-vertical sides and ends 20 and 21 respectively and a top 22, all of which are of uniform thickness. When the cover 19 is assembled on the base 11, the respective sides and ends 20 and 21 of the cover are adapted to make a snug fit about the perimeter of the vertical wall 14 of the platform, the lower edges of the sides and ends of the cover being supported on the corresponding top-surfaces of the skirt 13, as indicated in Figs. 1 and 3.

Formed in that end wall of the cover 19 which corresponds to the slotted end of the base 11 and which is hereinafter referred to as the "rear end-wall 21" of the cover, are a pair of hinge elements 23, each of which constitutes an element of the articulated joint 16 and comprises an integrally-molded substantially-rectangular tongue depending from the lower edge 24 of the rear end-wall 21 of the cover. The tongues 23 are in the vertical plane of the rear end-wall of the cover and in spaced parallel relationship to each other, as shown in Fig. 3, the lateral spacing of the tongues corresponding to the distance between the slots 15 of the base 11, each tongue being of slightly less width than the width of the respective slots, so as to make a free fit therein. The length of each tongue is such that its lower end is adapted to project downwardly below the cam-surfaces 18 of its respective pair of ribs 17, the lower extremity of each tongue having a transverse slot 25 molded therein, as clearly shown in Figs. 4 and 6. In the preferred construction, each slot 25 intersects the lower edge of its respective tongue and extends upwardly therein to a point such that its closed end is adjacent to but spaced slightly from the cam-surface 18 of its respective pair of guide-ribs 17 to provide a clearance space for the purpose hereinafter described. As indicated in Fig. 4, in the event the molded plastic tongues 23 of the cover 19 are extremely thin, it is preferable to reinforce the slotted ends of the tongues by molding them of greater thickness than the upper reaches thereof, thereby to provide sufficient material for forming slots 25 of appreciable dimensions in the tongues.

The slots 25 are provided to receive guide-pins 26 which are adapted to be assembled in the respective slots 25 of the tongues 23 after the latter have been inserted in the slots 15 of the base, to

complete the articulated joint. To this end, each pin 26 is substantially equal in length to the distance between the outer faces of its respective pair of guide-ribs 17, whereby the opposite ends 5 of each pin are adapted to slidably engage the respective cam-surfaces 18 thereof, as indicated clearly in Fig. 3. Moreover, each pin 26 is preferably formed of a plastic material and is adapted to be secured in its respective slot by a drop of cement 27 or equivalent fastening-means. Although the slot-and-pin construction illustrated herein is highly satisfactory and preferred from the standpoint of economy in manufacture, it is within the purview of the invention to provide other equivalent means.

The cover 19 of the receptacle is in its closed position on the base 11, as shown in Fig. 1, and may be temporarily locked therein by suitable latching-means (not shown). When the cover 20 is closed, the guide-pins 26 in the slotted ends of the tongues 23 are spaced slightly below the adjacent cam-surfaces 18 of their respective ribs 17 by an amount equal to the aforementioned clearance space. By this expedient, the finite 25 thickness of the tongues 23 is taken into account so as to permit the cover to swing freely from its closed position to its open position. When the cover is unlatched and swung upwardly, the bottom edge 24 of its rear wall 21 acts as a fulcrum 30 and as a consequence, the transverse pins 26 of the hinge-elements 23 are brought into cooperative engagement with the arcuate cam-surfaces 18 of the ribs 17 so as to hold the fulcrum-edge 24 of the cover in pivotal engagement with the 35 adjacent top or bearing-surface of the skirt 13. As the cover rotates, the ends of the transverse guide-pins 26 slide along the arcuate cam-surfaces 18 of the ribs 17 through an arc of substantially 90°, the tongues 23 of the cover moving 40 from a substantially-vertical position to a substantially-horizontal position, as indicated by the broken lines in Fig. 4 and as provided for by the vertical and horizontal reaches of the slots 15. Further rotational movement of the cover 45 relative to the base is effectively prevented by engagement of the extremities of the tongues 23 with the underside of the platform 12, the latter constituting in effect stop-means to limit the 50 rotation of the cover. The all-plastic articulated joint 16 thus provides a smooth-acting snug-fitting pivoted fastening-means for securing the plastic cover 19 to the plastic base 11 of the receptacle.

Although the articulated joint 16 shown in 55 Figs. 1 through 7 is satisfactory and wholly successful, it is also within the purview of the invention to form each hinge-element of the joint as a bifurcated tongue such as shown at 23a in Figs. 7 and 8. In this instance, the spaced parallel legs 28 of each bifurcated tongue 23a are arranged to extend through suitable slots 15a of the base 11a and to engage on opposite sides respectively of a guide-projection comprising a single relatively-thick molded rib 17a on the underside of the base 11a, the former having an arcuate cam-surface 18a adapted to be engaged by the intermediate portion of a transverse guide-pin 26a cemented or otherwise secured at its opposite ends in slots or apertures in the lower extremities of the bifurcated tongues 23a.

Fig. 9 illustrates an additional modification of the invention and relates particularly to the preferred construction of the arcuate cam-surfaces of the guide-ribs when the thickness of the walls 75 and hinge-elements of the cover are appreciably

greater than $\frac{1}{16}$ ". In such instances, the rear edge 29 of the rear end wall 21b of the relatively-thick cover 19b acts as the fulcrum thereof and as the cover is swung upwardly to its open position, the fulcrum-edge 29 will slide inwardly along the upper bearing-surface of the skirt 13b of the base 11b, as indicated by the broken line positions of the partially-opened cover in Fig. 9. Hence, in order to secure a smooth-acting snug-fitting hinged joint, compensation must be made for the sliding movement of the fulcrum-edge 29 and the resulting displacement of the guide-pins 26b at the extremities of the hinge-elements 23b. This may be accomplished by plotting successive positions of the guide-pins 26b for corresponding positions of the fulcrum-edge 29 of the cover as the latter is opened. By drawing a smooth curve through these plotted positions, the required curvature of the cam-surfaces 18b of the guide-ribs 17b may be obtained for insuring a smooth-acting, snug-fitting hinged joint. It will be noted, moreover, that by plotting the curvature of the cam-surfaces 18b, a minimum clearance space is required between these surfaces and the guidepins 26b.

The articulated joint or hinge of this invention has been described and illustrated as used in conjunction with the base and cover of a plastic receptacle or display case, but it will be understood that the articulated joint of this invention may be used for pivotally joining any equivalent frame-member to a corresponding base-member.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In an article of manufacture having a base-member provided with a slot and a cover-member: articulated-means to secure one edge of said cover-member in pivotal engagement with said base-member, said articulated-means comprising an element on one edge of said cover-member arranged to project through the slot of said base-member, a pair of arcuate projections on the underside of said base-member, said arcuate projections being arranged in spaced parallel relationship at opposite edges of said slot and a transverse guide-member carried by said cover-element, the opposite ends of said transverse member being arranged to slidably engage the respective arcuate projections of said base-member as said cover-member is rotated relative thereto.

2. In an article of manufacture having a base-member provided with a slot and a cover-member: articulated-means to secure one edge of said cover-member in pivotal engagement with said base-member, said articulated-means comprising an element on one edge of said cover-member arranged to project through the slot of said base-member, a pair of ribs on the underside of said base, said ribs having arcuate cam-surfaces subtending an angle of substantially 90° and arranged in spaced parallel relationship at opposite edges of said slot and a transverse pin secured to said cover-element, the opposite ends of said pin being arranged to slidably engage the respective cam-surfaces of said ribs as said cover-member is rotated relative to said base-member.

3. In an article of manufacture having a base-

member provided with a pair of spaced slots and a cover-member: articulated-means to secure one edge of said cover-member in pivotal engagement with said base-member, said articulated-means comprising a pair of tongues on the said edge of said cover-member arranged to project through the respective slots of said base-member, two pairs of projections on the underside of said base-member, one pair of projections being arranged at opposite edges respectively of each slot and each projection comprising an arcuate cam-surface, and a transverse pin secured in the end of each tongue, the opposite end of each pin being arranged to slidably engage the corresponding cam-surfaces of the respective pairs of projections as said cover-member is rotated relative to said base-member.

4. In an article of manufacture having a base-member provided with a pair of spaced slots and a cover-member: articulated-means to secure one edge of said cover-member in pivotal engagement with said base-member, said articulated-means comprising a pair of tongues on the said edge of said cover-member, each tongue having a transverse slot therein, two pairs of projections on the underside of said base-member, one pair of projections being arranged at opposite edges respectively of each slot and each projection comprising an arcuate cam-surface subtending an angle of substantially 90° , and a pin secured in the transverse slot in the end of each respective tongue, the opposite ends of each pin being arranged to slidably engage the corresponding cam-surfaces of the respective pairs of projections as said cover-member is rotated relative to said base-member.

5. A hinge for securing a frame-member in pivotal engagement with a base-member having a pair of spaced slots therein, said hinge comprising a pair of tongues on one edge of said frame-member arranged to project through the slots of said base-member, two pairs of projections on the underside of said base-member, one pair of projections being arranged at opposite edges respectively of each slot and each projection comprising an arcuate cam-surface, and a transverse pin secured in the end of each tongue, the opposite ends of each pin being arranged to slidably engage the corresponding cam-surfaces of the respective pairs of projections as the frame-member is rotated relative to said base-member.

6. A hinge for securing a frame-member in pivotal engagement with a base-member having a pair of laterally-spaced slots in one edge thereof; said hinge comprising a pair of tongues on one edge of said frame-member arranged to project into the respective slots of said base-member, each of said tongues having a transverse groove in the lower end thereof, two pairs of projections on the underside of said base-member, one pair of projections being arranged at opposite edges respectively of each slot at substantially right angles thereto and comprising an arcuate cam-surface subtending an angle of substantially 90° , and

65 a pin secured in the transverse slot in the end of each tongue, the opposite ends of each pin being arranged to slidably engage corresponding cam-surfaces of the respective pairs of projections as said frame-member is rotated relative to said base-member.

7. An article of manufacture comprising a plastic base-member embodying a platform and a flange circumscribing said platform and joined integrally therewith by a substantially-vertical shoulder, said base-member having a pair of

spaced slots provided in one edge thereof, said slots intersecting both said flange and the corresponding portions of said shoulder; a plastic cover-member for said base, said cover-member being arranged to fit over said platform and to engage on said flange adjacent the base of said shoulder; and articulated-means to secure one edge of said cover-member in pivotal engagement with the slotted edge of said base-member; said articulated-means comprising a pair of plastic tongues formed integrally on one edge of said cover-member and adapted to project downwardly through the slots in said flange, each tongue having a transverse slot in its lower end, two pairs of arcuate molded rib-members on the underside of said base-member, one pair of ribs being arranged at opposite edges respectively of each slot and each rib comprising an arcuate cam-surface subtending an angle of substantially 90°, and a plastic pin secured in the transverse slot in the lower end of each tongue, the opposite ends of each pin being arranged to slidably engage the corresponding cam-surfaces of the respective pairs of ribs as said cover-member is rotated relative to said base-member.

8. A hinge for securing a plastic cover-member in pivotal engagement with a plastic base-mem-

ber having a pair of laterally-spaced slots therein, said hinge comprising a pair of plastic tongues integral with one edge of said plastic cover-member and arranged to project through the slots of said plastic base-member; two pairs of molded ribs on the underside of said plastic base-member, one pair of ribs being arranged at opposite edges respectively of each slot and each rib having an arcuate cam-surface subtending an angle of substantially 90°, and a plastic pin secured to the lower end of each integral tongue-member, the opposite ends of said plastic pins being arranged to slidably engage the corresponding cam-surfaces of said molded ribs as said plastic cover-member is rotated relative to said plastic base-member.
